UNITED STATES PATENT OFFICE.

ANTIME MOTTEAU, OF BUENOS AIRES, ARGENTINA.

GLASS-PANE HOLDER.

1,347,706.

Specification of Letters Patent. Patented July 27, 1920.

Application filed February 14, 1919. Serial No. 276,984.

To all whom it may concern:

Be it known that I, ANTIME MOTTEAU, a citizen of the French Republic, residing at No. 1272 Garay street, Buenos Aires, Argentina, have invented certain new and useful Improvements in Glass-Pane Holders, of which the following is a specification.

My invention relates to a novel means for holding in position the glass panes in metallic window frames and its object is to provide a simple and economical means whereby the window pane may be held in position before putting on the mastic, said means being capable of retaining such 10 glass panes, even in case the mastic should fall out of the frame.

To the above end there have been proposed heretofore different means, all of them, however, consisting in fixing to the 20 webs of the angle bars of the frame by means of screws, rivets, or the like, stops or retainers of any suitable form. This, however, considerably weakens the general structure, gives it disagreeable appearance, 25 and greatly increases its dead weight.

According to my present invention I attain the same results by making a longitudinal slot of suitable length along one web of certain of the bars of the frame and at 30 any suitable point of the same, and passing through the said slot a small metal strap which is then bent over against the surface of the glass.

Where slots for jointing have been already made in the webs of the bars, as is the case in the well known "fenestra" joints, and in those disclosed in my co-pending application for Letters Patent, Serial Number 276,983, filed of even date herewith, it is 35 convenient to use such slots, so as not to diminish the resistance of the general structure and to avoid making new slots.

In order that my present invention may be clearly understood and easily carried 40 into practice, reference will be made now to the accompanying drawings, in which,

Figure 1 is a sectional view of an iron frame of ordinary section provided with a holding device according to my present invention.

Fig. 2 is a like view of a "fenestra" iron frame,

Fig. 3 shows a modified construction wherein the holding device is inserted

through the upper cut of the "fenestra" frame and

Fig. 4 shows the holding device as applied to an iron frame according to my above-identified, co-pending application.

Similar characters of reference indicate 60 the same or like parts throughout the above figures.

It must be clearly understood that although the present device is shown and described as applied to specific frames and 65 profiles it may be also used in connection with all kind of suitable iron or other frames.

1 is a comparatively flexible metal strap, as for instance, a brass band which is inserted through a slot 2 in the web 3 of the angle-iron division bar of the frame, which slot may be made at any suitable point of the said web. When a deep slot is specially made for any purpose, the metal strap is 70 provided with a corrugation which fits exactly in the slot, but where the slots are, such corrugations may be dispensed with, the metal strap being already firmly imprisoned within the said slot. The other 75 web 4 of the bar provides a support for the glass panes to be fastened in place, this being true whether the panes rest directly upon the web 4 in Fig. 1, or are supported by the web of a second bar, which is separate from and disposed at right angles to the first bar, and which, in turn, is supported thereby, as in Figs. 2, 3 and 4.

Figs. 2 and 3 show the invention as applied to a "fenestra" frame, the metal strap 90 1 being inserted in the lower and upper slot respectively in the web of the division bar. Said strap is then bent upward or downward, as shown, and then over against the glass pane, which is thus held in position 95 by the same.

In the embodiment of Fig. 4, the metal strap 1 is inserted in the slot before fixing the rivets 5, the strap being firmly imprisoned by the said rivets.

While the strap-holding slot may be located at any suitable point in the web 3, as has already been stated, it is preferably formed in the said web 3 adjacent the junction of that web with the web 4, as indicated in Figs. 1, 2 and 4, in which instance the bends immediately adjacent the central portion of the strap will be interposed be-

tween the side faces of web 3 and the adjacent edges of the panes. In Fig. 3, the slot in which the strap is engaged is located comparatively close to the free longitudinal or outer edge of web 3.

Although the holding device has been shown and described in connection with slots relating to the joint, it is obvious that it may be also applied to slots made in any other parts of the iron webs and this without diminishing the resistance of the material or considerably increasing the dead weight of the structure.

Having now fully described and ascertained the nature of my present invention and in what manner the same is to be carried into practice, I declare that what I claim is:

1. Means for holding glass panes in frames, comprising a bar of angle section embodying a pair of longitudinal webs arranged at right angles to each other, one web providing support for a pair of panes at opposite sides of the other web, and the latter web being provided with a transverse opening; and a metal strap having its central portion mounted in said opening and its two end portions first bent vertically against the opposite side faces of the second-named web directly adjacent the open-

ing and then bent laterally in opposite directions away from said second-named web directly against the outer faces of the panes so as to lie flat thereagainst.

2. Means for holding glass panes in frames, comprising a bar of angle section embodying a pair of longitudinal webs arranged at right angles to each other, one web providing support for a pair of panes at opposite sides of the other web, and the latter web being provided adjacent its point of connection to the first-named web with a transverse opening; and a metal strap having its central portion fitted in said opening and its two end portions first bent upwardly against the opposite side faces of the second-named web directly adjacent the opening and between said side faces and the adjacent edges of the panes, and then bent horizontally in opposite directions away from said second-named web directly against the outer faces of the panes so as to lie flat thereupon.

In testimony whereof I affix my signature in the presence of two witnesses.

ANTIME MOTTEAU.
